L. MAISEL,
BATTERY HANDLAMP,
APPLICATION FILED MAY 14, 1920, RENEWED OCT. 5, 1921,
1,397,646. Patented Nov. 22, 1921.

UNITED STATES PATENT OFFICE.

LORENZ MAISEL, OF MADISON, WISCONSIN, ASSIGNOR TO BURGESS BATTERY COMPANY, OF MADISON, WISCONSIN. A CORPORATION OF WISCONSIN.

BATTERY-HANDLAMP.

1,897,646.

Specification of Letters Patent.

Patented Nov. 22, 1921.

Application filed May 14, 1920, Serial No. 381,271. Renewed October 5, 1921. Serial No. 505,566.

To all whom it may concern:

Be it known that I, LORENZ MAISEL, a citizen of the United States, residing at Madison, in the county of Dane, State of Wisconsin, have invented certain new and useful Improvements in Battery-Handlamps; and I do hereby declare the following to be a full, clear, and exact description of the invention, such as will enable others skilled in the art to which it appertains to make and use the same.

The present invention relates to battery hand lamps, and more particularly to that type in which the lamp is protected from shock or impact or other undue pressure by the battery.

The objects and advantages of the present invention will be made clear by the following detailed description, taken in conjunction with the accompanying drawings, wherein—

Figure 1 shows a complete battery candle:

Fig. 2 is a section through a hand lamp comprising a battery candle to which a reflector and lens have been added to alter the distribution of light from the incandescent lamp; and

Fig. 3 is an end view of the structure shown in Fig. 2 with the lens, reflector and head removed therefrom.

In the particular embodiment illustrated in the drawings the battery comprises a plurality of dry cells 1 and 2 arranged end to end in series relation, and contained within the usual cardboard tube 3. The naked bottom of the lowermost cell rests on and makes electrical connection with the coiled spring 4 carried by the metal cap 5, screw-threaded to the lower end of a tube 6, forming the body of the casing. This tube 6 may be of metal, as shown, or may be of hard fiber or other suitable material. At the front end of tube 6 and secured thereto, as by riveting, is a threaded collar 7, the front edge of which is preferably turned over to form a retaining flange 8.

At the front end of the casing, and preferably attached thereto permanently, as by being screw-threaded into collar 7 before the latter is riveted to tube 6, is a disk 9 of insulating material, such as fiber, serviceable as an abutment against which the top end of the battery bears and against which it is firmly held by the pressure of spring 4 at the bottom of the case. An opening in the

center of disk 9 accommodates the upper or carbon electrode 10 of the topmost dry cell.

Mounted on disk 9 is a conductor which may be in the form of a circular plate 11, fastened with nails 12, and having a curved integral finger 13 bent down into a slot in disk 9 to serve as a contact element coöperating with the curved front end 14 of a sliding finger 15 which can be manipulated in usual manner by a thumb button 16 mounted near the center of the casing.

Attached to conductor 11, as by soldering, is a spring 17, the upper end of which is soldered or otherwise fastened to the outwardly flaring edge of a support 18, into which is threaded or otherwise secured the base of an incandescent lamp 19. This spring 17 serves to conduct current from conductor 11 to one terminal of the lamp and holds the other or central terminal 20 of the lamp in yielding engagement with the top terminal 10 of the battery.

With the several elements constructed and assembled as above described, the circuit is as follows: from the upper battery terminal 10, through the lamp to its support or socket 18, thence through spring 17 to plate 11 and finger 13, and thence by way of sliding finger 15, case 6, cap 5 and spring 4 to the other terminal of the battery. This structure, as illustrated in Fig. 1, is completely operative as a battery candle and gives a well distributed light. However, for the purpose of obtaining from the battery lamp a relatively concentrated beam of light, there is provided an enlarged head having a threaded portion 21, screwed on to collar 7, and having a flaring portion 22 with a threaded cylindrical extension 23 terminating in a flange 24 on which the reflector and lens are seated. The usual threaded ring 25 holds the lens and reflector in place. The reflector 26 is not integral with the lamp socket or support 18 and, in fact, has no connection therewith. The opening at the center of the reflector is large enough to pass the lamp bulb and the lamp socket, and there is an air gap at 27 serving to insulate the reflector from the socket, for without this insulation the hand lamp, if otherwise constructed as shown in the drawings, would burn continuously.

Other objects and advantages of the construction described will be apparent to those skilled in this art, and changes in details of the several parts and in their grouping are

contemplated within the scope of the invention as defined by the appended claims.

I claim:

1. In a battery hand lamp, the combination of a casing, an abutment at the front end thereof, a battery of dry-cells placed end to end in said casing, a spring pressing said battery against said abutment, a lamp, and means yieldingly holding said lamp in direct electrical contact with the inner terminal of said battery. 70
2. In a battery hand lamp, the combination of a casing, an abutment at the front end thereof, a battery of dry cells, a spring at the bottom of said battery urging it against said abutment, a lamp protruding beyond said casing, and means yieldingly holding said lamp in electrical connection with one terminal of said battery. 75
3. In a battery hand lamp, the combination of a casing by which the hand lamp is carried, a battery abutment at the front end thereof, a battery of dry cells placed end to end in said casing, a spring in said casing pressing said battery against said abutment, a conductor on said abutment, a lamp, means yieldingly mounting said lamp on said abutment and in circuit with said conductor, and a switch between said battery and said conductor, substantially as described. 80
4. In a battery hand lamp, the combination of a casing, a battery abutment therein, a lamp, a socket for said lamp, said lamp and socket being movable with respect to said abutment and a reflector having a central opening through which the bulb of said lamp will pass, substantially as described. 85
5. In a battery hand lamp, the combination of a casing, a battery abutment therein, a lamp, a socket for said lamp, flexible means securing said socket to said abutment and a reflector for said lamp removable therefrom without disturbing the operative relation of said lamp to said battery, substantially as described. 90
6. In a battery hand lamp, the combination of a casing, a battery therein, an abutment at the front end of said casing, a spring at the bottom of said casing urging said battery against said abutment, a conductor on said abutment, a lamp, a socket therefor, a spring between said socket and said conductor and yieldingly holding said lamp in electrical connection with one terminal of said battery, and means for connecting the other terminal of said battery with said conductor. 95
7. In a battery hand lamp, the combination of a casing, a battery of dry cells placed end to end therein, an abutment permanently closing the front end of said casing, a spring at the bottom of said casing urging said batteries against said abutment, a conducting plate on said abutment, a lamp, a threaded socket for said lamp, a spring securing said socket to said plate and holding said lamp in yielding engagement with one terminal of the battery, and means for connecting the other terminal of said battery with said plate when the lamp is to be lighted. 100
8. In a battery hand lamp, the combination of a casing, an abutment at the front end thereof, a battery of dry cells pressing against said abutment, a lamp, means yieldingly holding said lamp in electrical connection with one terminal of said battery to form an operative battery candle, and an enlarged head adapted for attachment to said casing and provided with a reflector and lens to convert said candle into a searchlight, substantially as described. 105
9. In a battery hand lamp, the combination of a casing, an abutment at the front end thereof, a battery of dry cells, a spring at the bottom of said battery urging it against said abutment, a lamp, means yieldingly holding said lamp in electrical connection with one terminal of said battery, and a reflector for said lamp removable therefrom without disturbing the operative relation of said lamp to said battery, substantially as described. 110
10. In a battery hand lamp, the combination of a casing, a battery abutment therein, a lamp, means yieldingly mounting said lamp on said butment, a reflector having a central opening through which the bulb of said lamp will pass, and means for detachably supporting said reflector in operative relation to said lamp. 115
11. In a battery hand lamp, the combination of a casing, a battery abutment therein, a lamp, a socket for said lamp, said lamp and socket being movable with respect to said abutment, a reflector having a central opening through which said lamp will pass, and means for detachably supporting said reflector in operative relation to said lamp. 120
12. In a battery hand lamp, the combination of a casing, a battery abutment therein, a lamp, a socket for said lamp, flexible means securing said socket to said abutment, and a reflector for said lamp removable therefrom without disturbing the operative relation of said lamp to said battery. 125
13. In a battery hand lamp, the combination of a casing, a battery abutment therein, a lamp, a socket for said lamp, a conductor on said abutment, a spring electrically connecting said socket with said conductor, a reflector having a central opening through which said lamp will pass, and means for detachably supporting said reflector in operative relation to said lamp. 130
14. In a battery hand lamp, the combination of a casing, a battery therein, an abutment at the front end of said casing, a spring at the bottom of said casing urging said battery against said abutment, a conductor on said abutment, a lamp, a socket therefor, a

- spring between said socket and said conductor and yieldingly holding said lamp in electrical connection with one terminal of said battery, means for connecting the other terminal of said battery with said conductor, a reflector for said lamp having a central opening through which the bulb of the lamp will pass, and means for detachably securing said reflector to said casing.
- 10 15. In a battery hand lamp, the combination of a casing, a battery of dry cells placed end to end therein, an abutment permanently closing the front end of said casing, a spring at the bottom of said casing urging said batteries against said abutment, a conducting plate on said abutment, a lamp, a thread-
- ed socket for said lamp, a spring securing said socket to said plate and holding said lamp in yielding engagement with one terminal of the battery, means for connecting 20 the other terminal of said battery with said plate when the lamp is to be lighted, a reflector for said lamp having a central opening through which the lamp bulb will pass, and means detachably supporting said reflector on said casing in operative relation to said lamp, said reflector and its supporting means being removable from the casing without disturbing the operative relation of said lamp to said battery. 30

In testimony whereof I affix my signature.
LORENZ MAISEL.
